United States Patent Office

Des. 221,678
Patented Aug. 31, 1971

221,678

DISH DRAINER

Robert Gottsegen, 146 West St.,
Leominster, Mass. 01453

Filed July 16, 1970, Ser. No. 23,984

Term of patent 14 years

Int. Cl. D7—99

U.S. Cl. D44—29

FIG. 1 is a perspective view of a dish drainer showing my new design;

FIG. 2 is a plan view thereof;

FIG. 3 is a view in elevation from one end of the dish drainer, and

FIG. 4 is a view in elevation from the opposite end thereof.

I claim:

The ornamental design for a dish drainer.
